CAR DOOR

Frederick C. Heinen, Chicago, Ill., assignor, by
mesne assignments, to The Youngstown Steel
Door Company, Cleveland, Ohio, a corporation
of Ohio

Application May 1, 1933, Serial No. 668,704

18 Claims.

(Cl. 20—22)

This invention relates to car doors.

It is an object of this invention to provide sliding car doors for railway house cars, said doors being so constructed as to obtain frictional engagement with a supporting track in the closed position of said doors.

A further object is to provide sliding car doors having longitudinally inclined members adapted to engage rolling means having rolling contact with a supporting track, said members in the closed position of the doors being out of engagement with said rolling means whereby said doors may be frictionally supported upon said track.

A further object is to provide sliding doors for railway house cars adapted to be supported upon balls for the major portion of their movement and adapted to be free of said balls and supported frictionally upon said car in the closed position of said doors.

A further object is to provide sliding doors having a member which is deformed to provide similarly inclined portions adapted to have rolling contact upon rolling means movable relative to said doors while permitting frictional support of said doors in the closed position thereof.

A further object is to provide sliding doors having secured thereto a straight member carrying longitudinally inclined means adapted to engage rolling means movable relative to said doors whereby said doors move freely during their travel to open and closed position and are frictionally supported in the latter position.

A further object is to provide sliding doors adapted for movement through the medium of relatively movable rolling means upon a straight uninterrupted supporting track, said doors in closed position being frictionally supported upon said track.

Other objects will become clear as the description of the invention proceeds.

In the drawings forming part of this specification:

Figure 1 is a partial elevation of a sliding car door embodying one form of the instant invention;

Figure 2 is a fragmentary enlarged elevation of the lower portion of the door in full closed position;

Figure 3 is a view similar to Figure 2, showing the door in full open position;

Figure 4 is a vertical section taken on line 4—4 of Figure 2;

Figure 5 is a vertical section taken on line 5—5 of Figure 2;

Figure 6 is a fragmentary elevation of a car

door showing a modified form of the invention;

Figure 7 is a fragmentary elevation showing the door illustrated in Figure 6 in full open position;

Figure 8 is a vertical section taken on line 8—8 of Figure 6;

Figure 9 is a partial elevation of a car door showing a further modified form of the invention;

Figure 10 is a vertical section taken on line 10—10 of Figure 9; and

Figure 11 is a vertical section taken on line 11—11 of Figure 9.

Referring to the drawings and particularly Figures 1 to 5 thereof illustrating one form of the instant invention the numeral 10 indicates a portion of the side wall of a railway house car in conjunction with which doors showing the invention are utilized. The side wall 10 is provided

with a door opening 11 which is adapted to be closed by means of a sliding door 12. The opening 11 is defined by the side plate 13, front and rear door posts 14 and 15 and the floor 16 of the car. The door 12 is supported for longitudinal movement relative to the side wall 10 of the car

upon a track 17 supported from the side sill 18 of the car by means of a plurality of track supporting brackets 19. Disengagement of the upper portion of the door 12 from the side wall 10 is

prevented by means of the retaining bar 20 secured to the side plate 12 and provided with a downwardly extending flange 21 adapted to overlap the upper margin of the door. Disengagement of the lower portion of the door from the car side is prevented by means of the bracket

members 22 and 23 which, as clearly shown in Figures 4 and 5 of the drawings, are provided with upwardly extending flanges 24 and 25, adapted to overlap the depending flange 26 of the track. In its closed position the door is adapted

to be fastened to the side wall 10 by means of a latching structure indicated generally by the reference numeral 27. An opening and closing arrangement comprising a bracket 28 secured to the side wall 10, an arm 29 pivoted to said bracket

and an operating lever 30 pivotally carried by the door adjacent the forward vertical margin thereof is utilized in connection with the door in order to impart initial opening and final closing movements thereto. As clearly illustrated in Figure 1

of the drawings the door 12 is preferably, though not necessarily, provided with a plurality of horizontal corrugations 31 which merge at their ends into vertical corrugations 32 and 33 formed in

the door inwardly of the vertical edges thereof.

In the closed position of the door it is supported preferably through the medium of the bracket members 22 and 23 frictionally upon the track 17. During the opening and closing movements 5 of the door it is supported upon antifriction means, preferably in the form of balls 34, disposed upon and having relative movement with respect to the track 17. When the door is frictionally supported in its closed position the weight 10 thereof is carried directly by the track or upon a member secured to the track so that the balls 34 are relieved of such weight. During the movement of the door, however, the door is disengaged from the track and positioned upon the balls. 15 One form of the invention utilizing the principle above described is illustrated in Figures 1 to 5 of the drawings. A longitudinally extending member or track 35 is secured preferably to the lower margin of the door. This member 35 comprises a vertical flange 36 by means of which said member is riveted as indicated at 37 to the door. A downwardly and outwardly inclined flange 38 depends from the vertical flange 36 and is provided with a downwardly and inwardly inclined flange 39 and constitutes therewith a substantially inverted V shaped section within which the balls 34 are adapted to be seated during movement of the door. A substantially vertical flange 40 may depend from the flange 38. 20 The member 35 is deformed so as to provide rearwardly extending inclined portions 41 and 42, as illustrated in Figure 2 of the drawings. These portions may be provided by bending the member 35 as indicated at 43 and 44. By this arrangement of the member 35 the door is adapted to have frictional engagement with the track 17 in the full closed position of said door, while the door may be disposed upon the balls for movement thereon toward open position by means of a relatively slight rearward movement of the door. 25 This movement may be imparted to the door by actuation of the operating lever 30 which, by its engagement with the bracket 28, will impart the necessary movement to the door and position the door upon the balls 34. 30 The operation of the door from the foregoing description will be apparent. The operation of the starting arrangement will impart an initial opening movement to the door and transfer the weight thereof from the track to the balls. When 35 this has been accomplished the door may readily be moved to any desired open position. The operation of the starting arrangement brings about engagement between the member 35 and the balls 34, this engagement being maintained during the opening and closing movements of the door until the door reaches its full closed position when it is again supported directly by the track. In this position the balls are moved to the 40 point of highest inclination of the member 35 so that they are relieved of the weight of the door. For the purpose of maintaining the balls in their proper relationship a spacer 45 may be utilized. In order to prevent undesirable shifting of the balls and the spacer toward closed position a stop is employed, this stop preferably taking the form of a rivet 46 driven through the track 17 as illustrated in Figure 2 of the drawings. It is to be observed that in the full open 45 position of the door, as illustrated in Figure 3 of the drawings, the door will abut a plurality of back stops 47, one of which is shown in this figure of the drawings, while the front margin thereof will overlap the rear door post 15 so as to expose the entire door opening. 50

A modified form of the invention is illustrated in Figures 6, 7 and 8 of the drawings. In place of the member 35 there is secured to the lower margin of the door a Z-bar 48 positioned with its flanges 49 and 50 in vertical planes and the web 51 extending outwardly from the door. As in the previously described form of the invention the Z-bar 48 is deformed so as to provide the rearwardly inclined portions 52 and 53. The balls 34 are disposed upon the track 17 and are adapted to have rolling engagement with the web 51 of the Z-bar in the opening and closing movements of the door. The balls 34 are maintained in their proper spaced relationship by means of the spacer 45. In this modification, as well as in the previously described form, the brackets 22 and 23 are adapted to be positioned upon the track 17 in the full closed position of the door and to serve additionally to prevent escape of the balls by extending across the ends of the members 35 and 20 48, as clearly illustrated in Figures 4 and 8 of the drawings. The door 12, as shown in Figure 7 of the drawings, will expose the full door opening in the open position of said door. 25

Figures 9 to 11, inclusive, illustrate a further modified form of the invention. In this form a Z-bar 54 having a vertical flange 55 by means of which said Z-bar is secured to the door, a horizontally disposed web 56 and a vertical flange 57 depending therefrom, is utilized. An angle 30 member 58, arranged with one flange extending downwardly, is secured to the underside of the web 56 of the Z-bar. A plurality of channel members 59 positioned on opposite sides of the center line of the door are secured to the Z-bar 54. 35 These channel members 59, as clearly shown in Figure 9 of the drawings, are so arranged as to incline toward the rear of the door. This arrangement may be effected by means of the insertion of a substantially wedge shaped wooden 40 filler 60 between the channel members 59 and the angle member 58. A plurality of balls 34 are utilized in this form of the invention in order to support the door during its travel, these balls as in the previous modifications being maintained 45 in spaced relation by means of the ball spacer 45.

The door 12 embodying the considered form of the invention is shown in its full closed position in Figure 9 of the drawings. It will be apparent from this figure that in such position the door rests upon and is frictionally engaged with the track 17. It will be apparent, furthermore, that in the closed position of the door the supporting balls are relieved of the weight of the door. The construction illustrated for obtaining 50 this result preferably takes the form of outward swedging of the flanges of the channel members 59 as indicated at 61 in Figure 10 of the drawings. If desired, instead of the outward swedging of the flanges these flanges may be coped 60 so as to provide for the disengagement of the balls from the channel members 59 in the full closed position of the door. The downwardly extending vertical flange 57 of the Z-bar 54 and the depending flange of the angle member 58 confine the supporting balls upon the track and prevent disengagement of said balls therefrom and inward displacement of said balls upon the track. In view of the fact that the mode of operation 65 of the door constructed in accordance with the present form of the invention is the same as that described with reference to the first form of the invention no further mention thereof is here made. 70

It is apparent that numerous changes and 75

modifications in the details of the invention will be clear to those skilled in the art. It is intended, therefore, that all such modifications and changes be comprehended within this invention, 5 which is to be limited only by the scope of the claims appended hereto.

I claim:

1. In combination, a sliding door, antifriction means, means supporting said antifriction means, 10 said door being provided with portions longitudinally inclined relative to said supporting means adapted to have engagement upon said antifriction means during the travel of said door, said door being frictionally supported in the closed position thereof.
2. In combination, a sliding door, a track, antifriction means having rolling engagement with said track, said means being capable of longitudinal movement relative to said door, portions 20 inclined relative to said track provided on said door adapted to support the same upon said antifriction means during the travel thereof, said door being frictionally supported in closed position.
3. In combination, a sliding door, a track having a horizontally positioned uninterrupted tread, antifriction means disposed upon said tread for relative longitudinal movement with respect to said track and said door, means secured to and adapted to support said door upon said antifriction means, said means being inclined upwardly and rearwardly relative to said track whereby said door will be supported upon said antifrictional means during the travel of said door and be disengaged from said antifrictional means and frictionally supported upon said track in the closed position of said door.
4. In combination, a sliding door, antifriction means, means for supporting said antifriction means, said door in its closed position being frictionally supported upon said supporting means whereby said antifriction means is relieved of the weight of said door, means for transferring the weight of said door to said antifriction means, said door having a member rigidly secured thereto and adapted to have peripheral engagement with said antifriction means during the travel of said door.
5. In combination, a sliding door, a longitudinally extending rearwardly inclined member secured to the lower margin of said door, antifriction means, the inclination of said member being such that said door is frictionally supported in the closed position thereof with the weight of said door removed from said antifriction means and means for disposing said door upon said antifriction means with said member in peripheral engagement with said antifriction means.
6. In combination, a sliding door, a longitudinally extending rearwardly inclined member secured to the lower margin of said door, a track, a plurality of spaced balls disposed upon said track, means for maintaining said balls in spaced relation, said balls having longitudinal movement relative to said door and said track, said member being so inclined that the door is frictionally supported upon said track and the balls relieved of the weight of the door in the closed position thereof and means for disposing said door upon said balls for movement thereon.
7. In combination, a sliding door, a longitudinally extending rearwardly inclined member secured to the lower margin of said door, a track, a plurality of spaced balls disposed upon said track, means for maintaining said balls in spaced

relation, said balls having longitudinal movement relative to said door and said track, said member being so inclined that the door is frictionally supported upon said track and the balls relieved of the weight of the door in the closed position thereof and means for disposing said door upon said balls for movement thereon, said track having means adapted to limit travel of said balls in the direction of closing movement of said door.

5

8. In combination, a sliding door, a longitudinally extending member secured to a horizontal margin of said door, said member being deformed to provide portions inclined in the direction of opening movement of said door; each of said portions extending continuously for a distance 15 somewhat less than one-half the length of said door, each of said portions including angularly related flanges forming an inverted V shaped section, a ball seated in each section and a supporting track upon which said balls are disposed.

10

9. In combination, a sliding door, members secured to a horizontal margin of said door, said members being inclined in the direction of opening movement of said door and comprising angularly related flanges providing an inverted V 25 shaped section, a ball positioned in each section adapted for rolling engagement therewith, a supporting track, said balls being disposed upon said track for movement relative thereto.

20

10. A metallic door comprising, in combination with the panel thereof, a member secured to a horizontal margin of said panel, said member having portions lying on opposite sides of the center line of said door inclined in the direction 30 of opening movement of said door.

35

11. A metallic door comprising, in combination with the panel thereof, a member secured to a horizontal margin of said panel, said member having portions lying on opposite sides of the center line of said door inclined in the direction 40 of opening movement of said door, each of said portions embodying angularly related longitudinally extending flanges forming a substantially inverted V shaped section.

12. In combination, a sliding door, a track, a longitudinally extending Z-shaped member secured to the lower margin of said door, the flanges of said member extending vertically and the web thereof projecting outwardly from said door, said web being constructed to provide portions inclined in the direction of opening movement of said door, each of said portions extending continuously for a distance somewhat less than one-half the length of said door and a plurality of 50 balls disposed upon said track in rolling engagement therewith adapted to engage said inclined portions.

55

13. In combination, a sliding door, a track, a longitudinally extending member secured to a horizontal margin of said door, a plurality of 60 spaced downwardly opening channels secured to said member, said channels being inclined in the direction of opening movement of said door and a plurality of balls disposed upon said track in rolling engagement therewith, said balls having 65 rolling engagement with said channels to support said door during movement thereof.

65

14. In combination, a sliding door, a track, a longitudinally extending member secured to a horizontal margin of said door, a plurality of 70 spaced downwardly opening channels secured to said member, said channels being inclined in the direction of opening movement of said door and a plurality of balls disposed upon said track in rolling engagement therewith, said balls having 75

rolling engagement with said channels to support said door during movement thereof, the flanges of said channels being deformed and said balls lying contiguous to said deformations in the closed position of said door whereby said door will have frictional support upon said track and said balls will be relieved of the weight of said door.

15. In combination, a sliding door, a track, a substantially horizontally disposed longitudinally extending member secured to a horizontal margin of said door, a plurality of spaced downwardly opening channels secured to said member, said channels being inclined in the direction of opening movement of said door and a plurality of balls disposed upon said track in rolling engagement therewith, said balls having rolling engagement with said channels to support said door during movement thereof.
16. A metallic door comprising, in combination with the metallic panel thereof, a longitudinally extending member secured to a horizontal margin of said panel, said member having a substantially horizontally disposed outwardly directed flange, a channel member embodying downwardly extending flanges secured to the underside of said flange, said channel member being inclined toward the rear of said door.
17. In a railway house car, in combination, a car member having a door opening, a sliding door member adapted to close said opening, longitudinally extending rearwardly inclined track means secured to one of said members, antifriction means having peripheral engagement with said track means for supporting said door for longitudinal movement, the inclination of said member being such that said door is frictionally supported in one extreme position thereof with the weight of said door removed from said antifriction means and means for disposing said door upon said antifriction means for movement thereon.

18. In combination, a sliding door, a track having a horizontally positioned uninterrupted tread, antifriction means disposed upon said tread for relative longitudinal movement with respect to said track and said door, means secured to and adapted to support said door upon said antifriction means, said means being inclined longitudinally relative to said track whereby said door will be supported upon said antifrictional means during the travel of said door and be disengaged from and frictionally supported upon said track in an extreme position of said door.

FREDERICK C. HEINEN.
